Primary Examiner — Paula Allen Greene**CLAIM**

The ornamental design for a communications headset, as shown and described.

DESCRIPTION

FIG. 1 is a front top right perspective view of a communications headset showing our new design;

FIG. 2 is a front-bottom-left perspective view thereof;

FIG. 3 is a front view thereof;

FIG. 4 is a back view thereof;

FIG. 5 is a right-side view thereof;

FIG. 6 is a left-side view thereof;

FIG. 7 is a top view thereof; and,

FIG. 8 is a bottom view thereof.

The broken lines immediately adjacent to the shaded areas represent the bounds of the claimed design while all other broken lines are directed to environment and are for illustrative purposes only. The broken lines form no part of the claimed design.
